UNITED STATES PATENT OFFICE.

LEWIS W. BUBB, OF ST. LOUIS, MISSOURI, ASSIGNOR TO JESSE M. WILLIAMS, OF WEBSTER GROVES, MISSOURI.

GAS BURNER.

Application filed November 28, 1921. Serial No. 518,236.

To all whom it may concern:

Be it known that I, LEWIS W. BUBB, a citizen of the United States of America, a resident of the city of St. Louis and State 5 of Missouri, have invented certain new and useful Improvements in Gas Burners, of which the following is a full, clear, and exact description, reference being had to the accompanying drawings, forming a part of 10 this specification.

This invention relates to improvements in gas burners, the main object being to produce a gas burner whereby the gas is most effectively mixed with primary and secondary air. More specifically stated, an object is to facilitate the delivery of secondary air to discharge openings in the burner. A further object is to very effectively mix the primary air with the gas passing into the 20 burner.

With the foregoing and other objects in view, the invention comprises the novel construction, combination and arrangement of parts hereinafter more specifically described 25 and illustrated in the accompanying drawings wherein is shown the preferred embodiment of the invention. However, it is to be understood that the invention comprehends changes, variations and modifications 30 which come within the scope of the claims hereunto appended.

Fig. I is a vertical section illustrating the lower portion of a boiler equipped with a gas burner embodying the features of this 35 invention.

Fig. II is a front elevation of a portion of the boiler, the front wall of the combustion chamber being removed to show one of the burner supports.

Fig. III is a view similar to Fig. II with the front wall of the combustion chamber secured to the boiler.

Fig. IV is a view similar to Figs. II and III, showing the adjustable burner support 45 which closes the burner-receiving opening in the front wall.

Fig. V is a transverse section showing the burner in the combustion chamber.

Fig. VI is a horizontal section taken approximately on the line VI—VI in Fig. IV.

Fig. VII is a vertical section on the line VII in Fig. IV.

Fig. VIII is an enlarged horizontal section, partly in elevation, showing the 55 burner.

Fig. IX is a section taken approximately on the line IX—IX in Fig. VIII, showing the gas supply pipe which does not appear in Fig. VIII.

Fig. X is a transverse section showing 60 one of the burner tubes.

In the drawings, I have shown a portion of a sectional boiler including hollow sections 1, 2 and 3 having inner faces formed as shown most clearly by Fig. V to provide a 65 combustion chamber 4 having vertical side faces 5 at opposite sides of a twin burner B. As shown by Fig. V, the twin burner has inclined side faces located adjacent the vertical faces 5 to provide flaring inlets for 70 secondary air, and the burner can be adjusted vertically without varying the width of these inlets.

To permit vertical adjustment of the burner, the rear wall of the combustion chamber 75 is provided with a vertical row of recesses 6. The rear end of the burner B is provided with a projecting abutment 7 adapted to be inserted into any one of the recesses 6. These recesses are formed in different horizontal planes and they provide burner-supporting seats whereby the rear end of the burner can be supported in corresponding horizontal planes.

The adjustable means for supporting the 85 front end of the burner comprises a vertically adjustable closure plate 8 adapted to receive the inlet pipe 9 extending from the burner. The front wall of the combustion chamber is provided with a large burner-receiving opening 10 (Figs. IV and VII) normally closed by the vertically adjustable plate 8. The closure plate 8 is adjustably secured to the front wall of the combustion 90 chamber by means of an upper bolt 11 and lower bolts 12, said bolts passing through plate 8 and also through said front wall, the latter being provided with vertical rows of holes 13 (Figs. I, III and IV) adapted to receive said bolts. The bolts can be shifted 95 from one hole to another to support the closure plate 8 in different positions. In all of these positions, the plate 8 closes the burner-receiving opening 10 (Figs. III and VII) and it supports the front end of the 100 burner. The burner is provided with integral lugs 14 (Figs. I, VI and VII) into which the bolts 12 are screwed.

Each adjustable closure plate 8 has an air inlet controlled by a door 15 (Figs. I, IV 110

2 and VII), said door being adjustable to regulate the delivery of secondary air through the opening 10 (Figs. III and VII) which leads into the combustion chamber to supply air at points above the burner. Each door 15 comprises a marginal frame hinged at the top and provided with a fine screen 16 through which air is admitted when the door is closed. Each burner B comprises a 10 pair of parallel gas-conducting tubes 17, integrally connected together, each of said tubes having oppositely inclined flat side faces converging to its flat narrow top face. The tubes 17 are adjacent to each other to 15 form a restricted air inlet between them (Fig. V) and the adjacent inclined faces of the tubes are extended upwardly from the narrowest portion of said inlet to provide an upwardly flaring air passageway leading 20 to the upper edges of the tubes.

As shown by Figs. VIII and X, the upper edge of each gas-conducting tube is provided with two longitudinal rows of discharge openings 18, the openings in each 25 row being staggered with respect to the openings in the other row. The inclined side faces of each tube 17 are provided at their upper margins with longitudinal rows of air-conducting grooves 19 terminating at the 30 top face of the tube, and the upper end of each of said grooves is preferably formed opposite to a discharge opening 18 in one of the rows of openings and between two discharge openings 18 in the other row.

35 The secondary air rising at the inclined side faces of the burner tubes 17 is permitted to pass through the grooves 19 to the top faces of the tubes at points between and adjacent to openings 18 from which the 40 gaseous fuel is discharged, so the secondary air is very effectively delivered to and mixed with the fuel at the base of each flame.

The secondary air is admitted to the lower 45 portion of the combustion chamber through ports 20 (Figs. III, IV and VI) formed in the front wall of the combustion chamber. 21 designates vertically adjustable closures (Figs. IV and VI) adapted to control the admission of air at the ports 20.

50 A gas supply pipe 22 (Figs. I and IX) is connected to the inlet pipe 9 through the medium of a return bend R having a substantially U-shaped tapering passageway 23 provided with a relatively large open intake 55 end 24 for the admission of air and a smaller discharge end 24' leading to the inlet pipe 9. A nozzle 25 is screwed into the return bend R so as to extend into the relatively small end portion of the tapering passageway. The gas supply conductor has an outlet passageway 26 at the bottom (Figs. VIII and IX) leading to the nozzle 25. The nozzle and the inlet pipe 9 are in horizontal alignment with the relatively small discharge end 24' of the tapering passageway

23, and both ends of this passageway lie in the same horizontal plane.

When the burner is in service a stream of gas is discharged from nozzle 25 and a body of primary air is drawn into the relatively large intake end 24 of the tapering passageway 23 and discharged with the gas passing to the inlet pipe 9. A relatively large body of air can freely enter the large intake end of passageway 23 and this air is gradually compressed in the tapering passageway as it passes into and around the stream of gas issuing from nozzle 25. By admitting the air in this manner, I deliver a relatively large body of primary air to the gas, and this is very desirable, the primary air commingled with the gas in the burner being more effective than the added body of secondary air which enters the flame from points outside of the burner. Moreover, the gas is very thoroughly mixed with the primary air admitted through the tapering U-shaped passageway 23.

An inexperienced person should not regulate the admission of primary air to the return bend R, so this regulation is preferably determined by an expert who arranges a suitable annular bushing 27 in the relatively large end of the tapering passageway 23, said bushing being screwed into the return bend so that it can be removed and replaced by another bushing if further adjustment is desired.

Since the nozzle 25 is supplied with gas 100 through an outlet 26 (Fig. IX) at the bottom of the gas supply conductor, the gas-controlling valve (not shown) can be conveniently located at a point remote from the nozzle, and in this event air will not commingle with the gas in the supply conductor 105 22 when the controlling valve is closed. This is due to the fact that air will not rise through the gas outlet 26 at the bottom of the gas conductor. As a consequence, whenever the gas is turned on, gas alone will be 110 discharged from the nozzle 25 and this tends to prevent a back fire in lighting the burner.

I claim:

1. A gas burner comprising a pair of parallel gas-conducting tubes integrally connected together and provided with discharge openings in their upper edges, each of said tubes having oppositely inclined side faces converging to its upper edge, said tubes being adjacent to each other to form a restricted air inlet between them, and the adjacent inclined faces of said tubes being extended upwardly from the narrowest portion of said inlet to provide an upwardly flaring air passageway leading to said upper edges.

2. A gas burner comprising a pair of parallel gas-conducting tubes integrally connected together and provided with discharge openings in their upper edges, each

- of said tubes having oppositely inclined 5 side faces converging to its upper edge, said tubes being adjacent to each other to form a restricted air inlet between them, the adjacent inclined faces of said tubes being extended upwardly from the narrowest portion of said inlet to provide an upwardly flaring air passageway leading to said upper edges, and each of said inclined faces being flat and provided at its upper margin with air-conducting grooves terminating at the upper edge of the burner at points adjacent to the discharge openings.
- 10 3. A gas burner having an inlet for a mixture of gas and air, and a passageway leading to said inlet, said passageway having an open air intake for the admission of air, a gas-nozzle mounted in said passageway and arranged to discharge gas into said inlet, and a gas conductor having an outlet at the bottom leading to said nozzle, said gas conductor being arranged at an angle relative to said passageway leading 15 to said inlet.
- 15 4. A gas burner comprising a pair of parallel gas conducting tubes integrally connected together and provided with discharge openings in their upper edges, each of said tubes having oppositely inclined 20 side faces converging to its upper edge, said tubes being adjacent to each other to form a restricted air inlet between them, the adjacent inclined faces of said tubes being extended upwardly from the narrowest portion of said inlet to provide an upwardly flaring air passageway leading to said upper edges, each of said inclined faces being flat and provided at its upper margin with air conducting grooves terminating at the upper edge of the burner at points adjacent to the discharge openings, said tubes being provided with an open end 25 for the admission of air, a gas nozzle mounted in the passageway through said tubes and arranged to discharge gas into said inlet and a gas conductor having an outlet at the bottom leading to said nozzle, said gas conductor being arranged at an angle relative to said passageway in said tubes.
- 20 25 30 35 40 45 50
- In testimony that I claim the foregoing I hereunto affix my signature.
- LEWIS W. BUBB.
